Primary Examiner — T. Chase Nelson*(74) Attorney, Agent, or Firm* — Sterne, Kessler, Goldstein & Fox P.L.L.C.(57) **CLAIM**

The ornamental design for a shoe, as shown and described.

DESCRIPTION

FIG. 1 is a bottom perspective view of a shoe showing our new design;

FIG. 2 is a bottom view thereof;

FIG. 3 is a side view thereof;

FIG. 4 is another side view thereof;

FIG. 5 is a front view thereof;

FIG. 6 is a rear view;

FIG. 7 is a bottom perspective view of another embodiment of a shoe showing our new design;

FIG. 8 is a bottom view thereof;

FIG. 9 is a side view thereof;

FIG. 10 is another side view thereof;

FIG. 11 is a front view thereof; and,

FIG. 12 is a rear view thereof.

The broken lines in the Figures show portions of the shoe that form no part of the claimed design.
